COMBINED REEL, HANDLE AND ROD UNIT

Francis M. Drake, 5319 N. Hoyne Ave., Chicago, Ill.

Filed Oct. 24, 1962, Ser. No. 72,244

Term of patent 14 years

(Cl. D31—4)

FIG. 1 is a side elevational view of a combined reel, handle and rod unit showing my new design;

FIG. 2 is a front elevational view thereof;

FIG. 3 is a fragmentary rear elevational view thereof;

FIG. 4 is a bottom view thereof;

FIG. 5 is a top plan view thereof;

FIG. 6 is a fragmentary perspective view of the reel and handle portions of the article.

The rod portion is shown broken away in FIG. 2, for convenience of illustration.

The present application is a continuation-in-part of my prior application Serial No. 68,977, filed February 26, 1962, for Spinning Reel and Rod Assembly, now abandoned.

I claim:

The ornamental design for a combined reel, handle and rod unit as shown and described.
